UNITED STATES PATENT OFFICE.

GEORGE A. SLAYTON, OF CUYAHOGA FALLS, OHIO, ASSIGNOR TO THE FALLS RIVET COMPANY, OF SAME PLACE.

FRICITION-CLUTCH.

SPECIFICATION forming part of Letters Patent No. 367,856, dated August 9, 1887.

Application filed June 9, 1887. Serial No. 240,608. (No model.)

To all whom it may concern:

Be it known that I, GEORGE A. SLAYTON, of Cuyahoga Falls, State of Ohio, have invented a new and useful Improvement in Friction-Clutches, of which the following is a specification.

My invention is designed as an improvement on the clutch shown in Letters Patent No. 308,872, December 9, 1884, to W. D. Brock, whereby the operation of the same is improved and the two jaws are made adjustable relatively to each other.

Figure 1 represents a longitudinal section through the center of a pulley and clutch mechanism containing my invention. Fig. 2 is a side view of the pulley and clutch mechanism.

a is a shaft. *b* is a pulley, which revolves freely on the shaft between the collars *c* and *c'*. *d* is an arm secured to the shaft and extending radially therefrom. *e* is a flange mounted upon the pulley, and which is gripped by the jaws of the clutch. *f* and *g* are respectively the clutch-jaws, which are faced with wood or any similar suitable material, and which are mounted upon slides *f'* *g'*. These slides are provided with guideways in any suitable manner upon the opposite faces of the arm *d*, so that the slides *f'* *g'* may slide freely to and from the center of the shaft. The parts are so arranged that the flange *e* comes between the jaws *f* and *g*.

h is a lever, which is pivoted to the arm *d*, and which is provided at each extremity with set-screws *i* and *j*. At *k* it is pivoted to the slide *g'*.

l is a projecting piece cast on the slide *f'*, upon which the end of the set-screw *i* rests.

The end of the set-screw *j* rests upon a cam-shaped projection, *m*, which constitutes the short arm of the lever *n*. This lever *n* is pivoted to the arm *d* at *n'*, and the extremity of its long arm is pivoted to the link *o*. The other end of this link *o* is pivoted to a sliding collar, *p*, which is connected with a suitable shifter.

In the arrangement shown in the drawings the jaws of the clutch have released the flange of the pulley; but by forcing the collar *p* toward the collar *c'* the long arm of the lever *n*

will be thrown upward, causing the cam projection *m* to raise the arm of the lever *h*, which rests upon it, through the set-screw *j*. This movement carries the slide *g'* upward until the jaw *g* presses against the inside of the flange *e*. The same movement causes the set-screw *i*, operating upon the projection *l*, to carry the slide *f'* downward until the jaw *f* presses upon the exterior of the flange *e*.

By having the adjustment between the lever *h* and one or both of the slides carrying the jaws a great advantage is attained, in that the position of each jaw may be adjusted in reference to the other, so that under the action of the lever *h* each jaw will grip the flange simultaneously and with the same pressure. Thus, with the arrangement shown in the drawings, if it should be found that the inside jaw engages the flange before the outside jaw, it is only necessary to tighten the set-screw *i*, whereas to remedy the opposite difficulty it is only necessary to loosen the set-screw. This set-screw *i* might be arranged in the connection between the slide *g'* and the lever *h*, instead of in its present position. The amount of motion of both of the jaws under the action of the cam projection *m* may be regulated by the adjustment of the set-screw *j*.

I have described only one arm *d*, with its connected clutch mechanism; but it is obvious that two or more of the same may be employed in connection with the same pulley.

What I claim as my invention, and desire to secure by Letters Patent, is—

The combination, with a shaft and a loose pulley adapted to run freely on said shaft, of a clutch rigidly secured to said shaft, having two inversely-moving radial jaws adapted to engage one upon the periphery and the other against the interior of the pulley-flange, said jaws being connected by lever *h*, which is operated from a shifter through the lever *n*, and a set-screw, *i*, being interposed in the connection between the lever *h* and one of said jaws, whereby said jaws may be adjusted relatively to each other, substantially as described.

GEORGE A. SLAYTON.
